UNITED STATES PATENT OFFICE

133,047

DESIGN FOR A GAME DEVICE

Frank L. Weiss, New York, N. Y.

Application November 14, 1941, Serial No. 104,148

Term of patent 3½ years

To all whom it may concern:

Be it known that I, Frank L. Weiss, a citizen of the United States, residing at county of Bronx, city and State of New York, have invented a new, original, and ornamental Design for a Game Device, of which the following is a specification, reference being had to the accompanying drawing, forming part thereof.

Fig. 1 is a perspective view of a game device embodying my new design.

Fig. 2 is a top plan view thereof.

I claim:

The ornamental design for a game device, as shown.

FRANK L. WEISS.
